UNITED STATES PATENT OFFICE.

RICHARD W. RAFTIS, OF CHICAGO, ILLINOIS, ASSIGNOR OF ONE-SIXTH
TO EDWARD P. EASTMAN, OF CHICAGO, ILLINOIS.

SUBWAY OR TUNNEL CONSTRUCTION.

No. 834,322.

Specification of Letters Patent.

Patented Oct. 30, 1906.

Application filed April 27, 1906. Serial No. 314,015.

To all whom it may concern:

Be it known that I, RICHARD W. RAFTIS, a citizen of the United States, residing at Chicago, in the county of Cook and State of Illinois, have invented a new and Improved Subway or Tunnel Construction, of which the following is a specification.

My invention relates more particularly to that class of subways or tunnels in which extreme dryness is a desirable feature, but is applicable on account of its cheapness of construction to all types of subways or tunnels, and has for its object to produce a tunnel or subway which will be impervious to moisture and which will prevent the condensation of moisture upon the inner wall of the said tunnel and to accomplish the above results in an exceedingly inexpensive manner.

The means of accomplishing the above results may be more easily comprehended by having reference to the accompanying drawings, which are hereunto annexed and are a part of this specification, in which—

Figure 1 is a cross-section of a tunnel or subway, showing my improved construction in use. Fig. 2 is an enlarged detail view in section on line X X in Fig. 1. Fig. 3 is a section showing a portion of the arch in enlarged detail.

Similar figures refer to similar parts throughout the entire description.

In Fig. 1 the wall of the tunnel is constructed of a mass of concrete 1, which forms the sides and arch of the tunnel or subway. Metal binding members may be used, if necessary, in its construction. The base consists of two layers 2 and 3 of concrete, having a row of hollow tiles 4 put in between the two layers. It is necessary that the upper layer 2 should be of sufficient thickness to prevent the traffic from crushing the course of hollow tile 4. Within the layer of concrete which forms the outer surface of the side walls and arch 1 erect an inner layer of tile, which is formed, as better seen in the detail views, with a main body portion 5, which is formed with hollow openings 6 extending therethrough. The main body is rectangular and has on one side securing-arms 7, 8, and 9. These arms extend outwardly and have on their adjacent faces inwardly-projecting lugs or shoulders 10. These shoulders are formed by angles 11, which are forty-five degrees and extend from a point 12 slightly above

the side faces 13 of the main body portion 5. Practice has shown that the best results are obtained by using an angle of forty-five degrees on these shoulders.

It is necessary as a rule in constructing tunnels or subways of concrete to erect a staging of timbers to support the concrete, and when brick is employed it is necessary not only to erect the staging, but to employ masons, and a very considerable amount of exceedingly skilled labor is employed in doing the masonry-work on tunnels so constructed. By the use of my improved construction no masonry-work is necessary at all and only the very cheapest labor is employed to set the tile instead of the skilled masons, as in other forms of construction, and where my construction is used it makes a perfectly dry subway or tunnel, which is not the case either of the brick or concrete construction except where hollow tile are built up on the interior of the walls, which again increases the expense, owing to the fact that it has to be put up by masons.

In constructing a tunnel utilizing my improvement after the staging is erected all that is necessary to do is to lay the tile loosely upon the staging, and then when the concrete is spilled in the hardening of the concrete does all of the work necessary to do to form a wall which will be impervious to moisture and upon whose inner surface no condensation will take place, and the whole results in a perfectly dry construction at a minimum of cost.

Having described my invention, what I desire to secure by Letters Patent is—

1. A tunnel or subway having its walls formed of an outer layer of concrete and an internal lining of tile, said tile being formed of a main body portion having openings therein, securing-arms projected from one of the side faces of the said body portion, said arms being provided with inwardly-extending shoulders, said shoulders being formed by an angle of forty-five degrees extending from a point upon the arm slightly beyond the side face of the body portion, for the purpose set forth substantially as described.

2. A tunnel or subway whose walls consist of the combination of concrete having a plurality of binding members located therein with an internal lining of tiles, said tiles consisting of a main body portion having an

opening therethrough, and a plurality of securing-arms projected from one of the side faces of the said body portion, said arms being provided with inwardly-extending shoulders, for the purpose set forth substantially as described.

3. A tunnel or subway having its side walls and arch formed by the combination of concrete with an inner lining of tiles, the said tiles consisting of a body portion having openings therethrough and securing-arms projected from one of the side faces of the said body portion, said arms being provided with inwardly-extending shoulders, said shoulders being formed by an angle of forty-five degrees extending from a point upon the arm slightly beyond the side face of the body portion, for the purpose set forth substantially as described.
4. A tunnel or subway having its side walls and arch formed by the combination of concrete with an inner lining of tiles, the said tiles consisting of a body portion having openings therethrough and securing-arms projected from one of the side faces of the said body portion, said arms being provided with inwardly-extending shoulders, said shoulders being formed by an angle of forty-five degrees extending from a point upon the arm slightly beyond the side face of the body portion, for the purpose set forth substantially as described.

five degrees extending from a point upon the arm slightly beyond the side face of the body portion, the bottom or floor wall being formed of two layers of concrete, having a layer of hollow tile located between the two layers, all combined and arranged substantially as set forth.

5. A tunnel or subway having its side walls and arch formed of the combination of concrete having a plurality of binding members located therein with an inner lining of tiles, the said tiles consisting of a body portion having openings therethrough and securing-arms projected from one of the side faces of the said body portion, said arms being provided with inwardly-extending shoulders, said shoulders being formed by an angle of forty-five degrees extending from a point upon the arm slightly beyond the side face of the body portion, the bottom or floor wall being formed of two layers of concrete, having a layer of hollow tile located between the two layers, all combined and arranged substantially as set forth.

RICHARD W. RAFTIS.
